ELECTRIC MEMORIAL LAMP

Alfonso A. Colletti, 95 Beckman Ave.,
North Tarrytown, N.Y. 10591

Filed Dec. 8, 1965, Ser. No. 122

Term of patent 14 years

(Cl. D48—20)

FIG. 1

FIG. 2

FIG. 1 is a front elevational view of an electric memorial lamp showing my new design; and

FIG. 2 is a top view of the electric memorial lamp with the cover removed.

The broken line showing of foliage in FIG. 1 is for illustrative purposes only.

I claim:

The ornamental design for electric memorial lamp, as shown and described.
